(57) CLAIM

The ornamental design for a trunk mounted flag holder, as shown and described.

DESCRIPTION

FIG. 1 is a perspective view of the trunk mounted flag holder of the instant invention;

FIG. 2 is a rear view thereof;

FIG. 3 is a front view thereof;

FIG. 4 is a right side view thereof;

FIG. 5 is a left side view thereof;

FIG. 6 is a bottom view thereof;

FIG. 7 is a top view thereof;

FIG. 8 is an enlarged rear view of the upper section of the trunk mounted flag holder with the flag clasp part removed; FIG. 9 is an enlarged top view of the upper section of the trunk mounted flag holder showing the flag clasp inserted; and, FIG. 10 is an enlarged perspective view of the lower section of the trunk mounted flag holder with the upper section with flag clasp removed.

The broken lines shown in the figures and the areas within the broken lines represent unclaimed environmental subject matter.
